PACKING CASE

Filed Dec. 18, 1926

INVENTOR:
15 Frederick Calot Holbrook,
BY *J. H. M. Clegg*,
his ATTORNEY

UNITED STATES PATENT OFFICE

FREDERICK CABOT HOLBROOK, OF DUMMERSTON, VERMONT

PACKING CASE

Application filed December 18, 1926. Serial No. 155,637.

This invention relates to packing cases of the general type adapted for the shipment of articles which are easily damaged by rough handling. The invention will be herein disclosed as embodied in a packing case designed especially for the shipment of apples and other fruits, although it will be understood that essentially the same construction is useful in the shipment of other articles.

10 It is the chief object of the invention to devise a packing case which will effectually protect the articles packed therein from damage during shipment, to facilitate the packing of the articles, and to provide a construction which can be manufactured at a reasonable expense.

15

The nature of the invention will be readily understood from the following description when read in connection with the accompanying drawings, and the novel features will be particularly pointed out in the appended claims.

In the drawings,

Figure 1 is a perspective view of a packing case constructed in accordance with this invention, the cover of the case being removed;

Fig. 2 is a vertical cross-sectional view through the case shown in Fig. 1; and

30 Fig. 3 is a perspective view of the packing case when ready for shipment.

The packing case shown comprises a container which may consist simply of a wooden or fibreboard box of an ordinary commercial form. A wooden box of a common construction is illustrated in the drawings, this box having ends 2 and 3, sides 4 and 5, a bottom 6, and a top 7. Located inside the box and against the four vertical walls thereof, are spacing members 8, 9, 10 and 11, respectively. These members preferably are made of corrugated paper board, such as that used in the manufacture of large cartons, although any equivalent material may be substituted for it.

45 Referring to the spacing member 8, as shown in Fig. 1, it will be observed that it consists of a sheet of corrugated paper board the opposite ends of which are bent or folded along lines of scoring at right angles to the main body of the sheet to form flanges which

bear against the wall 4 of the box. At about the middle of said member 8 the sheet of fibre board is folded to form another spacing flange 14 which is of approximately equilateral triangular form in horizontal cross-section, 55 the base of the triangle being spaced from the main part of the sheet, and connected to it by the diagonal members of the triangle. These flanges space the main body of the sheet from the wall 4. For a packing case of 60 the size ordinarily required for shipping apples, these spacing members are of such dimensions that only three flanges are required in each member. It is obvious, however, that for large sheets more of these spacing flanges 65 would be necessary.

The spacing member 9 is like the member 8, and the spacing members 10 and 11 are like each other and are substantially like the element 8 except that in the particular construction shown they are not quite as long. All of these spacing members are placed vertically in the box with the end flanges of one member abutting against the margin of the member which bears against the adjoining wall so 70 that they strengthen each other at the corners. Another spacing member 15, Fig. 2, like the member 8 is used in the bottom of the box, while still another of these members 16 is placed in the top under the cover 7. 75

This construction thus provides an inner chamber, the walls of which are formed by the spacing members, this chamber being separated from the walls of the box by an air space of considerable width. 80

The chamber so provided is divided into compartments suited to the requirements of the particular articles to be packed. In a box designed for shipping apples, or the like, I prefer to use for this purpose a series of trays 90 17, preferably made of corrugated paper board, each tray consisting of a bottom with four sides which may or may not be secured together, the sides being integral with the bottom but separated therefrom by lines of scoring which facilitate the folding of the sides into the proper position. The space in each tray is further divided by partitions 18 of corrugated paper board interlocked with each other and cooperating with the walls 95 100

of the trays to form a series of rectangular compartments, each of suitable size to receive an individual apple. In any one tray the compartments are practically uniform in size, and these compartments are filled with apples previously graded to an approximately uniform size which is slightly larger than the compartments. Thus the apples are held tightly in place and any movement of them in the compartments is prevented.

This construction effectually protects the apples or other articles packed from injury during shipment, the space between the inner chamber and the walls of the box, including the top and bottom, being particularly valuable for this purpose. At the same time the packing case is relatively light in weight due to the nature of the material used, and the case can be manufactured at a very reasonable expense.

The use of the trays and the partitions is of value not only in protecting the apples, but also in facilitating packing, since the individual trays can be packed prior to placing them in the boxes. This saves labor, and it also permits the packing of the trays at any convenient time and the subsequent stacking and storing of them, if desired, preparatory to packing the trays in the boxes in accordance with the orders received.

The central triangular flange 14 of each spacer is of slightly greater width than the end flanges 12—12. This, together with the fact that the packed trays are bulged or slightly larger in horizontal dimensions than the corresponding dimensions of the inner chamber in the box, results in bulging the sides 4 and 5 somewhat when the box has been packed, and also bulging the bottom 6 and top 7. The sides, bottom and top, therefore, are tensioned and this tension is useful in holding the entire contents of the box under compression. The flanges have ample strength to withstand the strain so imposed upon them. An unusually solid construction thus is provided which, due to the spacing and the nature of the interior construction, effectually prevents bruising of the apples or otherwise damaging the articles packed. This tensioning of the sides, top and bottom of the box also is useful in taking up any shrinkage which may occur. When the packing of a case has been completed the cover 7 is nailed on and, preferably, two steel bands 20, Fig. 3, then are placed around the entire box and their ends are overlapped and welded or fastened together by the fasteners used in box strapping machines.

In the drawings apples of one size only are shown. When it is desired to pack a smaller size of apples in the box shown, spacing members are provided which have wider flanges than those illustrated so that the dimensions of the inner chamber are reduced. The trays and partitions are, of course, cor-

respondingly changed in dimensions. In some cases also it is desirable to pack one-half of the box with apples of one size and the other half with a different size. This can conveniently be done by dividing the box internally into upper and lower sections, the spacing elements, trays and partitions in one section differing in dimensions from those in the other section and each being suited to the size of the apples packed in its particular section.

While I have herein shown and described the preferred embodiment of my invention, it will be understood that the invention may be embodied in other forms without departing from the spirit or scope thereof.

Having thus described my invention, what I desire to claim as new is:

1. A packing case of the character described, comprising a box, and a plurality of corrugated paper board spacing members inside said box, located closely adjacent to and parallel with the walls thereof, said members having flanges at the ends thereof and also between said ends serving to space the main body of each member from the walls of said box, whereby said members form an inner chamber in the box for the reception of the material to be shipped said intermediate flanges consisting of a portion of the member folded into approximately triangular cross-sectional form with the base of the triangular flange bearing against the wall of the box and connected to said member by the diagonal members of the triangle.

2. A packing case of the character described, comprising a box, and a plurality of paper board spacing members inside said box, located closely adjacent to and parallel with the walls thereof, said members having flanges both at the ends and also at the central part thereof, said central flanges being wider than the end flanges, whereby the main body of each member is spaced from the adjacent wall of the box, and the central part of each member is spaced farther from said wall than the end portions thereof.

3. A packing case of the character described, comprising a box, and a plurality of corrugated paper board spacing members inside said box, located closely adjacent to and parallel with the walls thereof, said members having flanges at the ends thereof, and also between said ends serving to space the main body of each member from the walls of said box, said members forming an inner chamber in the box with all of its walls spaced from the walls of the box, said intermediate flanges consisting of a portion of the member folded into approximately triangular cross-sectional form with the base of the triangular flange bearing against the wall of the box and connected to said member by the diagonal members of the triangle.

4. A packing case of the character de-

scribed, comprising, a box and paper board spacing members inside said box, located closely adjacent to and parallel with the walls thereof, said members having flanges at the ends thereof and also between said ends serving to space the main body of each member from the walls of the said box, the intermediate flanges being wider than the end flanges thereby to bulge the walls of the box and place the contents of the box under compression.
